[57] **CLAIM**

The ornamental design for a flexible cooler, as shown and described.

DESCRIPTION

FIG. 1 is a perspective view of a flexible cooler showing my new design;

FIG. 2 is a perspective view of an alternate embodiment of FIG. 1;

FIG. 3 is a perspective view of an alternate embodiment of FIG. 1;

FIG. 4 is a front elevation view of FIG. 1;

FIG. 5 is a front elevation view of FIG. 2;

FIG. 6 is a front elevation view of FIG. 3;

FIG. 7 is a rear elevation view of FIG. 1;

FIG. 8 is a rear elevation view of FIG. 2;

FIG. 9 is a rear elevation view of FIG. 3;

FIG. 10 is a top plan view of FIG. 1;

FIG. 11 is a top plan view of FIG. 2;

FIG. 12 is a top plan view of FIG. 3;

FIG. 13 is a right side elevation view of FIG. 1;

FIG. 14 is a right side elevation view of FIG. 2;

FIG. 15 is a right side elevation view of FIG. 3;

FIG. 16 is a left side elevation view of FIG. 1;

FIG. 17 is a left side elevation view of FIG. 2;

FIG. 18 is a left side elevation view of FIG. 3;

FIG. 19 is a bottom plan view of FIG. 1;

FIG. 20 is a bottom plan view of FIG. 2; and,

FIG. 21 is a bottom plan view of FIG. 3.
